(57) **CLAIM**

The ornamental design for a cleat, as shown and described.

DESCRIPTION

This application is related to U.S. patent application Ser. No. 09/771,461 filed on even date herewith, by Daniel Pellerin, entitled “UNIVERSAL CLEAT” which is incorporated herein by reference.

FIG. 1 is a rear perspective view of a cleat according to the present invention, with the cleat being oriented upside down from its position in use on a shoe;

FIG. 2 is a front perspective view of the cleat of FIG. 1;

FIG. 3 is a side elevation view of the cleat of FIG. 1, where the side elevation view of the opposite side is a mirror image of FIG. 3;

FIG. 4 is a front elevation view of the cleat of FIG. 1;

FIG. 5 is a rear elevation view of the cleat of FIG. 1;

FIG. 6 is a bottom plan view of the cleat of FIG. 1; and, FIG. 7 is a top plan view of the cleat of FIG. 1.
